COUPLING MEANS

Dale K. Scott, Atlanta, and Charles W. Walter, Griffin, Ga., assignors to Southern States Equipment Corporation, a corporation of Georgia

Filed Feb. 24, 1959, Ser. No. 795,206

3 Claims. (Cl. 220—23.4)

This invention relates to coupling means and more particularly to readily disjunctable coupling means especially adapted for interconnecting a pair of sliver cans to form a "train" whereby movement of the cans within a textile mill as a group is facilitated.

Frequently sliver cans are moved from place to place within the mill by an operator who simply slides the cans along the floor in groups of several cans. Each group may comprise some four or five cans. If the cans are pulled rather than pushed, suitable coupling means must be employed whereby a "train" of cans is formed. If the operator pushes the cans a suitable coupling is required which will effectively enable the operator to guide the foremost cans by controlling the rear-most one of the "train," particularly where the cans are of the large wheel-mounted type.

A principal object of the invention is to provide coupling means for coiler cans which is simple to connect and disconnect and which also forms a disjunctable coupling which is reliable and by which a guiding action can be imparted to the train of cans when the cans are pushed.

The invention in one form comprises a latch having a couple forming portion and a couple free portion, the latch being movably mounted on a support bracket secured to the upper rim of one coiler can. Securely affixed to the upper rim of another coiler can is a coupling bracket which is arranged to engage the couple forming portion of the latch to establish a connection between the cans, this connection being effected via the couple free portion of the latch which may disengage the coupling bracket by simply passing through a couple free passage in the coupling bracket.

For a better understanding of the invention, reference may be had to the following description taken in conjunction with the drawings in which Fig. 1 is an exploded perspective view of one form of coupling bracket comprising one feature of the invention; Fig. 2 is an exploded perspective view showing both the latch and its latch support which together constitute essential features of the invention; Fig. 3 is a side view of all the elements of the coupling means comprising the invention in assembled relation and showing in cross-section fragmentary portions of two cans coupled together by the invention; Fig. 4 is a top view showing structure similar to that depicted in Fig. 3; Fig. 5 is a side view of a clamp used to mount the elements comprising the essential features of the invention to the coiler cans; and in which Fig. 6 is a side view of the bracket depicted in Fig. 5.

As can best be seen in Figs. 1-3, two cans respectively designated by the numerals 1 and 2 are coupled together by the coupling structure generally designated in Fig. 3 by the numeral 3. In Figs. 1 and 2 the cans 1 and 2 respectively are schematically depicted by the dotted line circles. Affixed to the upper rim of can 2 is the latch support 4. Latch support 4 is secured to the upper rim

2

of can 2 by means of clamping elements 5. Each clamping element 5 is secured to the rim of can 2 by a single set screw 6 which clampingly engages the recesses 7 formed in the ends of latch support 4. Each element 5 frictionally engages the inner surface of the associated can. As can best be seen in Fig. 2 latch support 4 is provided with a pair of spaced apertured support elements 8 and 9. The aperture in support 8 is designated by the numeral 10 while the aperture in support element 9 is designated by the numeral 11.

Slidably mounted within the apertures 10 and 11 is the latch designated by the numeral 12. As can best be seen in Fig. 2, latch 12 is formed with a wide upper part 12A which is sometimes referred to as the couple forming portion of the latch and in addition the latch 12 is formed with the narrower lower part 12B which is sometimes referred to as the couple free portion of the latch. Also as can best be seen from Fig. 2, the upper extremity of latch 12 is provided with outwardly projecting shoulder portions 13 which constitute stop elements for limiting the downward travel of latch 12, the stops 13 being engageable with the upper surface of the support element 8. In like fashion the upper travel of latch 12 is limited by the stop 14 which may take the form of a rivet as is best seen in Fig. 3 and which may engage the lower surface of support element 9.

Mounted on can 1 adjacent the upper rim thereof is the coupling bracket generally designated by the numeral 15. As can best be seen in Fig. 1, the coupling bracket 15 is secured to the rim of can 1 by brackets 5 in a manner similar to the way in which the latch support 4 is secured to the upper rim of can 2. Set screws 6 of the brackets 5 simply engage the recesses 16 formed at the ends of coupling bracket 15 and the brackets 5 frictionally engage the inner surface of can 1. As can best be seen in Fig. 1, coupling bracket 15 is provided with a pair of spaced couple forming arms 17 and 18. Arm 17 is provided with an inwardly inclined portion 19, while arm 18 is provided with an inwardly inclined portion 20. The space between the inner ends of the inclined portions 19 and 20 of the spaced arms 17 and 18 designated in Fig. 1 by the letter "X" is referred to sometimes herein as a couple free passage, while the space enveloped between the base portion of the coupling bracket 15 and the couple forming arms 17 and 18 is sometimes referred to herein as a couple forming portion and the area in Fig. 1 is generally indicated by the letter "Y."

When cans 1 and 2 are brought together with the couple forming arms 17 and 18 of the coupling bracket 15 disposed between the support elements 8 and 9 of the latch support 4 while latch 12 is elevated, the narrow portion of latch 12 designated at 12B passes through the couple free passage designated by the letter "X" in Fig. 1 and into the couple forming passage generally designated by the letter "Y" in Fig. 1. Thereafter the latch 12 is allowed to fall downwardly by gravity so that the couple forming portion 12A thereof moves down into the space "Y" and effectively locks the cans 1 and 2 together. It will be understood that due to the rectangular shape of the area designated by the letter "Y" and due to the rectangular cross-section of the couple forming portion 12A of the latch 12 a secure coupling is established which enables the operator to guide the foremost can by pushing the rearmost can.

Of course there would be effective control should the operator exert a pulling force on the forward can, it being obvious that such a force would not uncouple the cans. Furthermore, it is clear that in order to uncouple the cans the latch 12 is simply raised manually.

While we have shown and described a particular form of the invention we do not wish to be limited thereto and intend in the appended claims to cover all such changes and modifications as fall within the true spirit and scope of the invention.

What we claim as new and desire to secure by Letters Patent of the United States is:

1. Disjointable coupling means for disjointably connecting a pair of similarly constructed coiler cans of substantially the same height, said coupling means comprising a latch support adapted to be mounted on one of said cans adjacent the upper rim thereof and having a pair of vertically spaced apertured support elements, a latch vertically slidable through the apertures in said support elements and having stop means adjacent its ends for respectively engaging said support elements, said latch having a wide upper part and a narrower lower part, a coupling bracket adapted to be mounted on the other of said cans adjacent the upper rim thereof and having a pair of horizontally spaced inwardly inclined couple forming arms disposed at a level between said support elements of said latch support, the vertical spacing between said support elements being substantially greater than the vertical dimension of said arms, said couple forming arms being arranged to envelope the narrower lower part of said latch when said latch is raised to its upper position and while said couple forming arms are disposed between said support elements, said latch being effective to form a coupling between said support elements and said coupling bracket when said latch is lowered sufficiently so that its wide upper part is opposite said couple forming arms.

2. Disjointable coupling means for disjointably connecting a pair of similarly constructed coiler cans, said coupling means comprising a latch support adapted to be mounted on one of said cans and having a pair of vertically spaced apertured support elements, a latch vertically slidable through the apertures in said support elements, said latch having a wide upper part and a narrower lower part and the configuration of said apertures and latch being such as to prevent substantial relative rotation between said latch and said support means irrespective of whether the wide or narrower part of said latch is opposite said support elements, a coupling bracket adapted to be mounted on the other of said cans and having a pair of horizontally spaced inwardly inclined couple forming arms disposed at a level between said support elements of said latch support, the vertical spacing between said support elements being substantially greater than the vertical dimension of said arms, said couple forming arms being arranged

to envelope the narrower lower part of said latch when said latch is raised to its upper position and while said couple forming arms are disposed between said support elements, said latch being effective to form a coupling between said support elements and said coupling bracket when said latch is lowered sufficiently so that its wide upper part is opposite said couple forming arms and while said couple forming arms are disposed between said support elements.

10 3. In combination, a pair of bodily movable coiler cans of comparable size and shape each having an upper rim, a latch support secured to the upper rim of one of said cans and having a pair of vertically spaced polygonally apertured support elements, a latch vertically slidable through said apertures and having a wide upper part and a narrower lower part in a tangential direction relative to said rim of said one can, said latch having a cross-section in a horizontal plane generally corresponding to but smaller than the apertures in said support elements whereby substantial rotation of said latch about its vertical axis relative to said latch support and its associated can is prevented, a coupling bracket mounted on the upper rim of the other of said cans and having a pair of horizontally spaced inwardly inclined couple forming arms disposed at a level between said support elements of said latch support, the inner surfaces of said arms and that part of said bracket adjacent the associated can rim being configured generally similar to the cross-sectional configuration of said latch, the vertical spacing between said support elements being substantially greater than the vertical dimension of said arms, said couple forming arms being arranged to envelop the narrower lower part of said latch when said latch is raised to its upper position and while said couple forming arms are disposed between said support elements, said latch being effective to form a coupling between said support elements and said coupling bracket when said latch is lowered sufficiently so that its wide upper part is opposite said couple forming arms, the similarity in configuration of said latch and of said bracket and arms being effective to prevent substantial rotation of said latch relative to said bracket and its associated can.
